UNITED STATES PATENT OFFICE

CHARLES I. JOHNSON, OF CHICAGO, ILLINOIS, ASSIGNOR TO NESTOR JOHNSON MANUFACTURING COMPANY, A CORPORATION OF ILLINOIS

TOE GUARD FOR ICE SKATES

Application filed August 11, 1930. Serial No. 474,418.

This invention relates to toe guards for shoes and more particularly for shoes which are attached to ice skates in order to protect the toes and adjacent portions of the foot 5 of the player from blows or other impacts when playing the rough and strenuous game of hockey.

The guard is in the form of a cap to fit 10 over the toe of the shoe, and may be applied either while the shoe is attached to the skate, or at the time of securing the shoe and the 15 skate together when the outfit is being assembled.

In my co-pending application, Serial No. 15 365,279, filed May 23, 1929, I disclose a toe 20 guard made of sheet metal or other relatively rigid and stiff material. This guard while it served the purpose very well, is subject to the objection that it is not resilient enough to absorb a blow and prevent the impact from 25 being felt by the foot of the player. Moreover such guard, especially when made of metal, is likely to chafe the portion of the shoe over which it is applied with the result 30 that the soft leather of which the shoe is usually made is damaged. Furthermore, a color if applied to the metal guard must be put on the guard in the form of a coating and the adhesion between the colored coat and 35 the metal is not sufficient to prevent checking or cracking of the color coat when repeatedly struck by a hockey stick or puck. A metal guard being stiff and rigid will not give with the foot of the player and if 40 clamped too tightly against the shoe is likely to cause discomfort to the player.

The object of my invention is to provide a 45 guard which will overcome the objections referred to, and in carrying out this object I make the guard of a moldable material of a character which while affording sufficient protection from a blow of a hockey stick or 50 puck, will have sufficient resiliency or cushion to absorb the blow and thus not transmit it with any discomforting effect to the toe of the player. I prefer to make the guard of mold- 55 ed rubber, either hard or semi-hard, and have it thick enough to afford the protection required. The guard is provided with means preferably in the form of angularly shaped

metal lugs whereby the guard may be attached by riveting either to the sole of the shoe or the sole plate of the skate or to both. The guard may be molded to the shape required to fit over the toe portion of the shoe, 55 and may be made of a size to merely cover the toe portion of the shoe, or it may be made larger so as to extend the protection up and over the instep, as well as along the side portions of the shoe, back over the ball of the 60 foot on the inside and over the little toe on the outside. The guard can also be perforated so as to reduce its weight, although it can be made without perforations, if desired. With a guard made of moldable material, the pigment required to color the guard whenever a color is required, can be incorporated directly in the material, and thus will not check or chip off when the guard is 65 struck by the stick or puck.

The invention consists further in the matters hereinafter described and claimed:

In the accompanying drawings,

Fig. 1 is a side view of an attached shoe and ice skate with a guard of my invention 75 applied over the toe portion of the shoe;

Fig. 2 is an enlarged vertical sectional view taken on line 2-2 of Fig. 1;

Fig. 3 is a top plan view of the toe portion of the shoe showing the guard thereon;

Fig. 4 is a bottom plan view of the guard removed from the shoe; and

Fig. 5 is a view similar to that of Fig. 1, showing a guard of a larger size so as to extend the protection up and over the instep, 85 and well along the opposite sides of the shoe.

In the drawings, 1 indicates a tubular ice 90 skate of the hockey type. 2 indicates the regulation shoe which is attached by riveting to the sole and heel plates 3, 4 of the skate.

The toe guard or protector of my invention is made of moldable material, such as rubber, either hard or semi-hard, and is shaped to fit in the manner of a cap over the toe portion of the shoe.

The guard has integrally connected top and marginal walls 5, 6. The marginal wall 6 is curved to fit about the rounded front end of the toe of the shoe, and also extends along the side portions of the shoe at the toe when 100

the guard is applied to the shoe. The top wall 5 extends rearward from the marginal wall over the upper portion of the shoe at the toe, and is suitably curved to conform to the contour of the toe portion of the shoe as shown in Figs. 1 to 3. The guard in its marginal top walls may be perforated with holes 7, 7 to reduce weight, and thus make the guard a relatively light fixture, so that when applied to the shoe, it will not add any appreciable weight to the skate.

The guard is provided with a plurality of inwardly extending members 8, 8 at its lower edge to be inserted between the sole plate 3 of the skate and the sole 9 of the shoe as shown in Fig. 2. The members 8, 8 are flat so that they may lie between the sole of the shoe and the sole plate of the skate, and are preferably rigidly secured to both by rivets 10, 10, one for each member as shown in Fig. 2. The members 8, 8 are located at the sides as well as at the front of the guard, so as to hold both portions from displacement with respect to the shoe and the skate when the guard is secured in place. The members 8 are preferably made of metal bent into angular form, and secured by rivets 11, 11 to the marginal wall 6 of the guard. The members 8 preferably lie on the inside of the guard, so that their lower inwardly extending portions need not be made long enough to extend under the lower edge of the guard, as would be the case should they be secured to the outer side of the guard. Moreover, with the members 8 on the inside of the guard, the outside of the guard is free of projections, and thus may have its outer surface made symmetrical to improve the appearance of the fixture.

The top wall 5 is slit or severed at its center as at 12 with the sides of the slit diverging from the marginal wall 6 so that the two sections of the top wall provided by the slit may be drawn toward each other to adjust the guard to the size and shape of the shoe with which it is used. To accomplish this, I provide an eyelet or opening 13 in each top wall section, and thread the lace 14 of the shoe through the eyelets, so as to draw the guard over the top of the shoe, and have it fit the same, as well as hold it firmly in place. A separate lace or cord could be used for this purpose if desired, thus freeing the lace of the shoe from this duty, and thus permitting the guard to be applied and removed from the shoe without the necessity of removing the lace of the shoe, should the members 8, 8 of the guard have a removable connection between the sole of the shoe and the sole plate of the skate.

In Figs. 1 to 4, I have shown the guard of a size and shape to merely fit over the toe portion of the shoe. In Fig. 5 I have shown a guard 15 made larger, so as to extend the protection afforded by the guard up and over the

instep of the shoe, and also well along the sides of the shoe to cover the ball of the foot on one side and the little toe on the opposite side. In this form the side portions of the guard extend either back to or beyond the cup 16 of the sole plate 17 of the skate, and the guard is provided at its sides and front with an appropriate number of members 8^a by which the guard is attached to the shoe and the skate in the same manner as illustrated in Fig. 2. The top wall of the guard 15 is severed or slit as in the guard of Figs. 1 to 4 and in extending well up over the instep of the shoe, the guard is provided with a row of eyelet openings 18, 18 on opposite sides of the slit to receive the lace 19 of the shoe in the same manner as the smaller guard heretofore described.

The marginal and top walls of the guard are made thick and rigid enough to afford the protection required. Being of moldable material, the guard may be molded from rubber either hard or semi-hard and thus give the guard sufficient resiliency or cushion to absorb the blows to which the guard is subjected in the game of hockey. Thus these blows will not be transmitted to the foot of the player, as is likely to occur when the guard is made of metal. With a moldable material, such as rubber, the guard also possesses sufficient yieldability in its wall structure to give with the foot of the wearer and thus avoid chafing and injury to the portion of the shoe encompassed or covered by the guard. The guard being light in weight will not add any burden to the foot of the player. With the guard made of a moldable material, the guard may be colored by incorporating the pigment desired in the material of which the guard is made, and thus the color will not crack or chip off when the guard is struck by a hockey stick or puck, or when coming into contact with other objects.

The guard may also be used with shoes attached to skates other than the tubular type, and I do no wish to be limited to the application of my invention to any particular type of skate or any particular form of shoe that may be used therewith.

The details of structure shown and described may be variously changed and modified without departing from the spirit and scope of my invention.

I claim as my invention:

1. The combination with a skate and a shoe attached thereto, of a guard fitting over the toe portion of the shoe to protect the same, said guard being made of moldable resilient non-metallic material.

2. The combination with a skate and a shoe attached thereto, of a guard fitting over the toe portion of the shoe to protect the same, said guard being made of molded rubber.

3. The combination with a skate and a shoe attached thereto, of a guard fitting over the

toe portion of the shoe to protect the same, said guard being made of a moldable resilient non-metallic material, and means carried by the guard, and fitting between the sole of 5 the shoe and the sole plate of the skate.

4. The combination with a skate and a shoe attached thereto, of a guard fitting over the toe portion of the shoe to protect the same, said guard being made of a moldable mate- 10 rial and having a marginal wall and a top wall, the latter being slit, so that the guard may fit shoes of different types and shapes.

5. The combination with a skate and a shoe attached thereto, of a guard fitting over the 15 toe portion of the shoe to protect the same, said guard being made of a moldable mate- rial and having a marginal wall and a top wall, said top wall being slit so that the guard may fit shoes of different types and shapes, 20 said top wall having openings therein on opposite sides of the slit wherein a lace or cord may engage with the guard to draw it over the shoe.

6. The combination with a skate and a shoe 25 attached thereto, of a guard fitting over the toe portion of the shoe to protect the same, said guard being made of a moldable resilient non-metallic material, members secured to the guard and extending inward therefrom to 30 engage between the sole of the shoe and the sole plate of the skate.

7. The combination with a skate and a shoe 35 attached thereto, of a guard fitting over the toe portion of the shoe to protect the same, said guard being made of a moldable mate- rial and angularly shaped metal members se- 40 cured to the guard on the inside thereof, and having portions extending inward from the guard to fit between the sole of the shoe and the sole plates of the skate.

8. A toe guard for shoes made of moldable 45 resilient non-metallic material, and having a top wall and a marginal wall, and angularly shaped members riveted to the marginal wall, and having portions extending inward there- 50 from at the lower edge of the guard.

9. The combination with a skate and a shoe 55 attached thereto, of a guard fitting over the forward portion of the shoe to protect the same, said guard having a top wall and a marginal wall, the top wall extending up and over the instep of the shoe and the side walls extending well along the sides of the shoe to protect the ball of the foot on the one side and the little toe on the opposite side.

In testimony whereof I affix my signature.
CHARLES I. JOHNSON.
